**COMBINED WRIST TELEPHONE, TRANSMITTER,
RECEIVER AND SIGNAL**

Isaac Heller, Maplewood, N. J., assignor to Robin Hood
Co., Newark, N. J., a corporation of New Jersey

Application May 6, 1955, Serial No. 35,865

Term of patent 14 years

(Cl. D26—14)

Fig. 1.

Fig. 2.

Fig. 3.

Fig. 4.

Fig. 2.

Fig. 5.

Figure 1 is a front elevational view of a combined wrist telephone, transmitter, receiver and signal showing my new design;

Figure 2 is a top plan view thereof showing one end of the wrist strap disconnected;

Figure 3 is a bottom plan view thereof;

Figure 4 is a rear elevational view thereof;

Figure 5 is an elevational view of one end thereof with the wrist strap connected; and

Figure 6 is an elevational view of the other end thereof.

I claim:

The ornamental design for a combined wrist telephone, transmitter, receiver and signal, as shown.
